(57) **CLAIM**

The ornamental design for a wireless communication device, as shown and described.

DESCRIPTION

FIG. 1 is a left front perspective view of a wireless communication device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a left front perspective view of the wireless communication device connected to an USB adapter.

The broken lines in the figures show portions of the wireless communication device that form no part of the claimed design. The dash-dot-dash lines in FIG. 7 represent the bounds of the claim and form no part of the claimed design. The broken lines depicting the features between the two sets of broken line boundaries in FIG. 7 and the broken lines depicting a USB adapter in FIG. 8 are directed to environment and form no part of the claimed design.
